UNITED STATES PATENT OFFICE

DANIEL M. ROTHENBERGER, OF LEESPORT, PENNSYLVANIA, ASSIGNOR TO DEVLIN W. DOEMER, OF READING, PENNSYLVANIA

MAUSOLEUM

Application filed April 18, 1928. Serial No. 270,881.

The invention relates particularly to that type of mausoleum in which there is a plurality of burial crypts associated in a single structure. The particular invention lends itself to ease and simplicity of construction and use, as well as to economy and stability. Those portions of mausoleum which are exposed to view may be of a rich or expensive material while those portions which are not exposed to view may be of cheaper material. A portion of the structure may be made of cement which is relatively cheap to buy and simple and easy to pour or erect. There is an advantage in structures having the elements which go to make up the individual crypts separate from the elements of the other crypts, thus it is not necessary to handle large and expensive elements. This type of construction may produce numerous joints in each crypt and, for sanitary reasons, it may be desirable to thoroughly and surely disinfect these joints. Provision may also be made for disinfecting and releasing fumes or gases formed in the individual crypts.

When the structure is made up of such independent elements it is desirable that they be rigidly held in place in the main structure and that the joints between the individual elements and the individual crypts be certainly, rigidly, and permanently supported.

These and other purposes may be carried out by the present invention.

In order to describe, but not limit, the invention an embodiment of it is shown in the accompanying drawings in which Figure 1 is a transverse vertical section through a mausoleum, a portion of which is omitted. Fig. 2 is a longitudinal vertical section of a single crypt. Fig. 3 is a longitudinal horizontal section of two crypts. Fig. 4 is a front plan view of two crypts. Fig. 5 is a transverse section through a corner where four crypts join. Fig. 6 is a horizontal section through a front corner where two crypts join. Fig. 7 is a vertical plan of a portion of a wall between two crypts. Fig. 8 is a vertical plan of a portion of a wall between two crypts. Fig. 9 is a transverse section through a wall between two crypts. Fig. 10 is a vertical plan of a portion of a wall between two crypts.

Fig. 11 is a vertical section through a portion of a wall at the rear of the crypts. And Fig. 12 is a vertical section through a front corner where two crypts join.

In Figure 1 is shown a mausoleum of four tiers of crypts, one above the other. Suitable heavy foundations, preferably of cement, are provided for the outer wall of the mausoleum. The upper portion of the outer wall may consist of a cement slab 2 faced with granite, marble or a suitable ornamental material 3. Within the wall 2 is a wall 4, preferably of cement, arranged to support the elements of the crypts. Between the walls 3 and 4 is a vertical ventilating channel 5 into which leads a passage-way 6 near the ground and from which leads a passage-way 7 near the roof 8. The passage-ways 6 and 7 are preferably provided with grilles or gratings 9 which may be made of brass, bronze, or other suitable noncorrosive metal.

The mausoleum may contain banks of crypts at the right, and at the left, and one may be added at the rear of the central hall or chapel 10, and the structure may be one or more stories high. There is shown a foundation 11 which surrounds the three sides of the central hall 10, placed a sufficient distance from the outer foundation wall 1 to cooperate with it in forming a support for the crypts.

The crypts may be made up of top and bottom plates or slabs 12 and side walls or slabs 13. The walls 4 act as backs for the crypts and may be covered with plates or slabs 14 corresponding in material and finish to the walls of the crypt. Each crypt will preferably be large enough to contain a casket 15 and may be provided with a closing slab 16 and an ornamental inscription plate 17, which may be plain or ornamented. Passing through the walls 4 are channels 18 to carry noxious fumes from the crypts into the vertical ventilating channel 5. The walls of each crypt may be structurally separate from the walls of the other crypts.

In Fig. 5 I show one method of building up the crypts. The side wall 13 of a lower crypt may have placed upon it a strip of noncorrosive metal or other suitable material 19 which as indicated in Fig. 2 may extend from

end to end of the crypt. In order to insure a sanitary joint, a layer of fibre 20 which may be saturated with a disinfectant, extends throughout the length of the plate 19. Upon 5 this is placed the side wall 13 of the upper crypt directly above the side wall 13 of the lower crypt. It will be noted that plate 19 extends beyond the sides of the wall 13. And upon these extensions at each side, covered 10 with the fibre 20 are placed the plate 12 which forms the ceiling for the lower crypt and the floor for the upper crypt. Upon these and resting upon strips of fibre 21 are metal strips 22 which, as indicated in Figs. 2 and 3, may 15 extend throughout the entire length of the crypt. This arrangement is made rigid and held together by bolts 23 passing through holes in the plates 22, 21, 12, 20, and 19 and extending through holes in the upper arms 20 of brackets 23^a which are placed at suitable intervals along the walls 13 so as to brace, support, and hold in place the entire arrangement. The inner lower corner of the plates 22 may be cut away throughout their length 25 as at 24 so as to provide channels for containing a suitable disinfecting fluid, which may be introduced through suitably disposed holes 25. By this arrangement the disinfecting fluid may be renewed at any time before 30 the crypt is sealed. The slabs or plates 12 are spaced slightly away from the upright walls 13 leaving channels 26 so that the disinfecting fluid in the channels 24 may saturate the fibre sheets 20 as well as the fibre sheets 21. In the rear, the channels 24 communicate 35 with channels 18 passing through the rear walls 4 into the ventilating channel 5. In order to prevent the disinfecting fluid from passing out through the channels 18, they are inclined upward so as to form traps 27. Any disinfecting fluid that does pass out 40 will pass down into the extension 60 forming a chamber at the bottom of the shaft 5.

In general it is desirable to have each crypt 45 separate from each other crypt and thoroughly and effectively disinfected therefrom as indicated above. It occasionally becomes necessary or desirable to throw two or more crypts into a single chamber. Such an occasion may arise when it is desired to have the bodies of two or more members of a family 50 in immediate proximity. The structural support desired from the side walls 13 may be maintained if a removable panel is provided in the wall of any desired shape and dimensions so as to afford not merely communication 55 between the adjoining crypts but to give the effect of a single large crypt.

Such a removable panel is indicated at 28 60 in Figs. 1, 2, 8, 9, and 10. In order to allow the panel 28 to be removed from either side of its containing wall 13 I may make the plate 28, whatever its size or shape, substantially the same size and shape as the aperture 65 in the wall 13. Surrounding the plate 28

and covering on one side the joint between it and the wall 13 is a frame 29, preferably made of strips of suitable noncorrosive metal, underlaid with a fibre strip 30, suitably saturated with a disinfectant. Through the 70 frame 29 pass bolts 31 the nuts 32 of which rest against and hold in place the frame 29. The bolts 31 extend through the plate 28 and are provided with heads 33 which rest against one element 34 of an angle bar 35. The element 34 of the bar 35 rests against the wall 13 and the opposite element 36 rests against the plate 28, so that by this element 75 the plate 28 is held rigidly and in a sanitary manner in position to close the aperture in the wall 13. The heads 33 of the bolts 31 are long but narrow, and where last bolt passes through the element 34 it is provided with a slot 37. By this arrangement it will be seen that when the head of the bolt is in the position indicated in Fig. 8, the structure is held assembled, but if the bolt is turned 80 so that the head lies at a right angle to the position shown in Fig. 8 it will enter the slot and allow the angle iron 35 to be removed 85 when the plate 28 may be removed toward the left of Fig. 9. If it is desired to remove the plate 28 toward the right of Fig. 9, of course, it will only be necessary to remove the nuts 32 from the bolts, thus freeing 29 which when removed, will allow the panel 28 to be moved toward the right of Fig. 29.

It will be noted from Figs. 1, 2, and 3, that the inner ends of the top, bottom, and side walls 12 and 13 may extend into and be set 90 in the cement of the supporting wall 4. Thus imparting rigidity to the whole structure. The rear plates 14, however, may merely rest against and be cemented to the walls 4, but it is preferred that they be more rigidly held in place by means of lugs or dowels 38 set in seats 39 and drilled into the top, bottom, and side walls 12 and 13. These lugs 38 preferably are cylindrical at their bases which seat in the holes 39 in the walls but are cut away so as to be semicylindrical in their 95 projecting portions. The plates 14 may rest against the flat sides of these projecting portions and be held in place by wires 40 passing around the lugs 38 and then beyond the plates 14 being turned down as at 41. Likewise in this arrangement the plates engage the lugs and hold them rigidly in place and against removal or displacement. By this arrangement the plates 14 are held rigidly and permanently in place and are so set when the cement of the wall 4 is poured. This arrangement is shown more clearly in detail in Fig. 11 where is also shown an auxiliary disinfecting device which may or may not be 105 employed but is especially useful when some method of connecting the walls is used other than that herein shown.

This consists of a bottle 42 having an upwardly and downwardly curved neck 43 into 110

which extends one end 44 of a tube, the other end 45 of which extends through the wall 4 into the ventilating channel 5. The outer dimension of the tube 44 is less than the inner dimension of the neck 43 and gases in the crypt will thus be forced to rise to the mouth or upper end of the passage 44 where they may be caused to mix and mingle with the gases given off by the disinfecting fluid 46 in the bottle 42 before passing into the ventilating duct 5.

The arrangement for closing the crypt after the body has been placed in it is shown in detail in Figs. 6, 7, and 12. Means similar to those employed for placing the slabs 14 in place may be employed for holding the inner sealing plates 16. To this end lugs 38^a similar to the lugs 38 are placed in holes 39^a drilled in the top, bottom and side walls 12 and 13 and turned with the flat sides of their projecting ends toward the outside of the crypt, that is, toward the hall 10. The lugs 38^a are surrounded by wires 40^a holding the sealing plate 16 in place against lugs 38^a. The outer ends 41^a of the wires 40^a are turned down against the plate 16 so as to rigidly hold it in place where it may be permanently sealed by cement or other means.

Beveled slots 47 may be provided in the top, bottom, and side walls 12 and 13, and likewise slots 48 may be provided in the sides of the outer ornamental or inscription plates 17. Wires 49 having upturned ends 50 and upturned intermediate portions 51 may be put in place around the edges of the opening and the plates 17 then slid into position. The distance between the upturned ends 50 and upturned intermediate portions 51 of the wires 49 is such that the slots 47 may be engaged by one of the upturned portions and the slots 48 by the other. These slots being elongated, allow the wire to be turned after plates 17 are in place, so as to cause the wire to properly engage the slots. The projecting ends 52 of the wire, the original position of which is shown in dotted lines in Fig. 7, may then be turned in along the edges of plate 17 and out of sight and so be concealed and covered by the appropriate cement or other sealing means which may be applied to permanently hold plate 17 in place. The ends turned into the opening along the edges of the plate 17 keep the wires from turning so that the upturned portions cannot be disengaged from the slots 47 or 48 and thus the plates are held permanently in position.

It may frequently happen that the interior ornamentation of the hall 10 in the midst of the mausoleum, will differ in material or color or appearance from the walls 12 and 13 of the individual crypts. The plates 17, of course, may readily be made to correspond to the other portions of the hall 10. It may be desirable to similarly cover

and conceal the ends of the walls 12 and 13 with harmonizing material. In Fig. 6 is shown one way in which this may be done. The wall 13 is illustrated as terminating within the outer surface of the plate 17. In the outer end of the wall 13 is a dovetailed slot or recess 53. A corresponding dovetailed slot or recess 54 is formed in the ornamental covering strip or facing 55. Extending into both dovetailed slots 53 and 54 is a metal tie member 56 having expanded ends and arranged to hold the strip 55 in proper relation with the wall 13. The dovetailed slots and the joint between the two members, may, in addition, be filled with cement or other binding material.

The outer faces of the plates 17 provide space for names or other suitable memorials, and they may be plain or fancy or ornamented. As indicated in the left of Fig. 4, suitable urns or vases 57 may be, if desired, attached by a suitable means to said plates.

The various walls may be made of granite, marble, or other desired stone or of bronze or other noncorrosive metal or of any other suitable material. Likewise the plates, dowels, wires, bolts, brackets, etc., may be made of any suitable material but preferably of bronze or other noncorrosive metal. It is preferred to have the entire structure made of materials which substantially do not deteriorate and are not disintegrated or destroyed by exposure to air and moisture. Thus the mausoleum and its parts may be as nearly everlasting as possible.

Various changes, alterations, omissions and additions may be made in the various details here shown for illustrative purposes only.

I claim as my invention:

1. In a mausoleum, a cement wall, a plurality of crypts, and separate slabs having ends embedded in the wall and forming tops bottoms and sides for said crypts.

2. In a mausoleum, a plurality of crypts, separate slabs forming rear walls for the crypts, a concrete wall cast against said rear wall slabs, and separate slabs forming top bottom and sides to the crypt and extending into the concrete wall whereby they are securely and permanently held in position.

3. In a mausoleum, a crypt made up of separate slabs, means for holding the slabs rigidly and permanently in place, a layer of absorbent material in the joints between slabs, and means for supplying a disinfectant to the absorbent material.

4. In a mausoleum, a plurality of crypts made up of separate slabs, upright slabs forming side walls for lower crypts, metal plates on top of said side walls, horizontal slabs resting on the metal plates and forming tops for lower crypts and bottoms for upper crypts, vertical slabs resting on the metal plates and forming side walls for upper crypts, plates resting on the horizontal slabs

adjacent the upper vertical slabs, and means for fastening all of said members rigidly and permanently in place.

5. In a mausoleum, crypts made up of separate slabs forming top bottom and side walls, and means for disinfecting the joints between said slabs.

6. In a mausoleum, a plurality of crypts, separate slabs forming tops bottoms and side walls for the crypts, and a layer of disinfecting material in the joints between the slabs.

7. In a mausoleum, crypts, plates holding the elements of the crypts in position and extending from front to rear, channels in the plates for receiving a disinfectant, and apertures leading from the channels to the surface of the plates.

8. In a mausoleum, a crypt, separate slabs forming the top bottom and side walls of the crypt, a plate extending from front to rear of the crypt having a channel carrying a disinfecting fluid, a rear wall having therethrough a vent connected with the channel, and a trap in said vent.

9. In a mausoleum, a crypt, separate slabs forming the top bottom and side walls of the crypt, a plate extending from front to rear of the crypt having a channel carrying a disinfecting fluid, a rear wall having therethrough a vent connected with the channel, a trap in said vent, a ventilating channel back of said rear wall into which the vent opens, and a trap at the bottom of the ventilating channel.

10. In a mausoleum, a cement wall, a plurality of crypts, separate slabs having ends embedded in the wall and forming tops bottoms and sides for said crypts, and disinfecting means for closing the joints between the slabs.

11. In a mausoleum, a plurality of crypts, separate slabs forming rear walls for the crypts, a concrete wall cast against said rear wall slabs, separate slabs forming top bottom and sides to the crypt and extending into the concrete wall whereby they are securely and permanently held in position, separate slabs forming front walls for the crypts, and means for holding the front wall slabs securely and permanently in place.

12. In a mausoleum, a crypt made up of slabs, means made of noncorrosive metal for holding the slabs permanently together, and means for introducing disinfectant into the joints between slabs.

13. In a mausoleum, a crypt made up of separate slabs, means for holding the slabs rigidly and permanently in place, a layer of absorbent material in the joints between slabs, means for supplying a disinfectant to the absorbent material, and a vent for the disinfectant.

14. In a mausoleum, a crypt, a plate extending from front to rear of the crypt hav-

ing a channel carrying a disinfecting fluid, a rear wall having therethrough a vent connected with the channel and a trap in said vent, a ventilating channel back of said rear wall into which the vent opens, and a trap at the bottom of the ventilating channel.

15. In a mausoleum, a crypt, and a plate extending from front to rear of the crypt having a channel carrying a disinfecting fluid.

16. In a mausoleum, a plurality of crypts made up of separate slabs, upright slabs forming side walls for a lower crypt, metal plates on top of said side walls, horizontal slabs resting on the metal plates and forming tops for the lower crypts and bottoms for the upper crypts, vertical slabs resting on the metal plates and forming side walls for the upper crypts, plates resting on the horizontal slabs adjacent the upper vertical slabs, brackets engaging the lower upright slabs and the metal plates on top of the side walls, and means for fastening all of said members rigidly and permanently in place.
